UNITED STATES PATENT OFFICE

HENRY WILLIAM SAMUEL PALMER, OF GERRARDS CROSS, ENGLAND

PACKING SEALED CONTAINERS CONTAINING MILK OR OTHER SUBSTANCES

Application filed September 20, 1929, Serial No. 393,857, and in Great Britain July 9, 1929.

This invention relates to the packing for transport of containers of conical shape sealed at one end by a circular disc and at the other by pressing its opposite sides together to form a straight diametrical seam, the whole producing what may be termed a sealed wedge-cone shape container. These containers are usually made of light material made waterproof in any suitable manner for containing milk, cream or any other suitable substance, and it has been found in packing such containers together that they get damaged and in some cases broken during transport.

The method of packing these containers according to the present invention consists in placing them side by side in a cylindrical box or casing with their diametrical seams vertically arranged in the centre of the container, preferably in contact with a central column, and with their axes radiating from the column and with their circular bases engaging the sides of the cylindrical box or casing. In a modification of this method the containers are placed with their diametrical seams vertically arranged in vertical grooves provided for them in a column arranged in the centre of the box or casing.

The preferred method of carrying out the invention is illustrated by the accompanying drawings in which Figure 1 is a plan of the cylindrical box or casing showing three of the containers packed therein in radial position, Figure 2 is a sectional elevation of the box or casing and Figure 3 a plan of a removable longitudinally grooved cylinder for use as an abutment in the centre of the box or casing. In these drawings A is a cylindrical box or casing having a cylindrical wall or outer side *a* and a fixed central column *b* preferably provided with longitudinal grooves *b1*.

The containers of special shape which are to be packed for transportation in the box or casing A consist of cylindrical sides *c* which are sealed at one end by a disc or base *c1* and at the other by pressing the opposite sides together to form a straight diametrical seam *c2* which when the container is made of a light material such as waxed card or paper

are preferably covered by a strip of metal *c3* pressed tightly on the seam *c2*.

The longitudinal grooves *b1* instead of being formed directly in the column *b* may be formed in a separate cylinder *b2* as shown in Figure 3, which is arranged to fit on the column *b* and be removable therefrom. This enables the grooved member to be formed from sheet metal corrugated to form the grooves *b1*.

In filling the box or casing A with the containers *c* their sealed diametrical seams *c2* are placed vertically in the grooves *b1* to the column *b* and the diameter of the box or casing A is made such that the base ends *c1* engage each other and the cylindrical wall *a* so that they will all be held radially in position in the box or casing A in such a manner that they cannot injure each other during transport.

What I claim and desire to secure by Letters Patent is:—

1. A packing box or casing for the reception of containers of cylindrical shape sealed at one end by a circular disc and at the other by pressing its opposite sides together to form a straight diametrical seam, comprising a cylindrical box or casing, and a vertical column fixed in the centre of the box or casing, the column being of a depth corresponding to the length of the diametrical seam of the container, while the distance between the column and the walls of the box or casing corresponds to the axial length of the container so as to prevent radial movement thereof when they are arranged radially therein side by side.

2. A packing box or casing for the reception of containers of cylindrical shape sealed at one end by a circular disc and at the other by pressing its opposite sides together to form a straight diametrical seam, comprising a cylindrical box or casing provided with a central fixture for holding the diametrical seams of the container vertically in the centre of the box or casing and with the axes of the receptacles radiating therefrom and their circular ends engaging the cylindrical sides of the box or casing.

3. A packing box or casing for the reception

tion of containers of cylindrical shape sealed at one end by a circular disc and at the other by pressing its opposite sides together to form a straight diametrical seam, comprising a cylindrical box or casing and a vertically grooved column situated in the centre of the box or casing, the grooves in the column being of a length and width, corresponding to the length and thickness of the 10 diametrical seams of the containers while the distance between the depth of the grooves of the column and the walls of the vessel corresponds to the axial length of the containers so that they can be arranged side by side radially in the box or casing.

4. A packing box or casing for the reception of containers of cylindrical shape sealed at one end by a circular disc and at the other by pressing its opposite sides together to 20 form a straight diametrical seam, comprising a cylindrical box or casing, a vertical column situated in the centre of the box or casing, a removable externally and longitudinally grooved hollow cylinder fitting on the 25 column, the external grooves in the hollow cylinder being of a length and width corresponding to the length and thickness of the diametrical seams of the containers, while the distance between the depth of the grooves 30 in the removable cylinder and walls of the box or casing corresponds to the axial length of the containers so that they can be arranged side by side radially in the box or casing.

In witness whereof I affix my signature.
HENRY WILLIAM SAMUEL PALMER.
